UNITED STATES PATENT OFFICE.

HARRY HOWELL, OF WILMINGTON, DELAWARE.

DRIP-VALVE.

SPECIFICATION forming part of Letters Patent No. 458,189, dated June 2, 1891.

Application filed September 8, 1890. Serial No. 364,355. (No model.)

To all whom it may concern:

Be it known that I, HARRY HOWELL, a citizen of the United States, and a resident of Wilmington, in the county of New Castle and State of Delaware, have invented certain new and useful Improvements in Drip-Valves; and I do hereby declare that the following is a full, clear, and exact description of the invention, which will enable others skilled in the art to which it appertains to make and use the same, reference being had to the accompanying drawings, which form a part of this specification.

My invention relates to improvements in drip-valves for steam-engine cylinders for drawing off the water of condensation and in method of operating the same, and is more particularly adapted for use with locomotive-engines.

The object of the invention is to provide an improved construction of such valves whereby they are operated by steam or air pressure and the usual rods and levers for operating the same dispensed with.

The invention consists in the novel construction and combination of parts hereinafter fully described, and specifically pointed out in the claims.

In the accompanying drawings, Figure 1 is a central vertical section of a drip-valve constructed in accordance with my invention. Fig. 2 is a cross-section on the line $x-x$, Fig. 1. Fig. 3 is a sectional view of the relief-valve. Fig. 4 is a side view of a steam-cylinder, showing the location of the valve. Fig. 5 is an end view of the same.

The drip-valve is a double valve, and is designed to be placed underneath the cylinder in the center thereof and communicating by means of pipes with each end of the cylinder, as seen in Fig. 5, instead of having a valve at each end, as is ordinarily the practice. In the said drawings the body of the valve consists of an annular rim 1, countersunk or grooved on the sides to receive diaphragms hereinafter described.

The reference-numeral 3 designates the ends or heads of the valves, having lugs on their peripheries by which they are connected together by means of headed bolts 5 and nuts 6. These heads are provided with inwardly-

projecting peripheral flanges, which are provided with annular recesses corresponding with the recesses in the rim 1. Each of these heads is provided with an outwardly-projecting boss 7, having a central recess 8, communicating with the interior of the valve by means of aperture 9. The outer ends of these bosses are screw-threaded to receive a coupling 10, which is connected with a pipe 12, leading to the end of the cylinder, and intermediate with the ends of each boss is a flange 13, which forms the seat for a valve 14, having inwardly-projecting stem 16, passing through aperture 9 in the valve head or end 65 into the interior thereof. The valve is also provided with an outwardly-projecting stem 18, the outer end of which is received in a bearing 19, secured upon the interior of the coupling 10, and intermediate of this bearing 70 and the valve is a coiled spring 20, embracing stem 18, said spring forcing the valve into its seat and closing the same. Intermediate of the head or end of valve and the flange 13 is an opening 21 in the boss, communicating 75 with the atmosphere.

The numeral 22 indicates two diaphragms consisting of annular metallic disks, the peripheries of which rest in the annular recesses in the rim and ends of the valve, and 80 when the latter are bolted together these diaphragms are securely held at their peripheries. At the center of each diaphragm is a small disk 23, which rests against the end of the valve-stem 16, said disk being secured in 85 place by means of bolt 24 and nut 25. These diaphragms are provided with a series of concentric corrugations for the purpose of allowing them to vibrate without injuring their points of connection.

The numeral 26 designates a screw-threaded coupling or extension of the rim 1, having a central opening communicating with the interior of the valve. This coupling is connected with a pipe 27, leading to the engine-cab, provided with a suitable cock. The pipe 27 also connects with a compressed-air reservoir or with the steam-boiler.

Any ordinary three-way cock may be employed in connection with pipe 27, but I prefer the construction shown in Fig. 3, for which I have made a separate application for

Letters Patent of even date herewith, Serial No. 364,356, which it is not necessary to here describe in detail.

The operation of the invention is as follows: In its normal condition the valves 14 are seated by means of the coiled springs 20, thus closing communication between the cylinder and the atmosphere. When, however, it is desired to open the valves to allow the water of condensation to escape, the cock in pipe 27 is opened, allowing the steam or compressed air to escape into the interior of the valve, which, pressing the diaphragm outward, actuates the valve-stem 16, opening the valves and establishing communication between the cylinders and atmosphere and allowing the condensed water to escape through openings 21. The cock in the pipe 27 is what is known as a "three-way cock," so that when actuated to open the valves communication is established between said valves and the air-compressor or boiler; but when closed communication is established between the valves and atmosphere, so as to relieve the valves of back-pressure, as will be readily understood.

For the purpose of keeping the valves open when the engine is at rest, I provide the following means: The numeral 28 designates an eccentric-rod passing diametrically across the interior of the valve, one end being received in a recess in an inwardly-projecting boss 29. The other end of this rod passes through the rim 1, and is provided with an operating handle 30. This rod is oblong in cross-section and near the handle end is provided with a beveled annular flange 31, fitting in a beveled seat in coupling 32, through which the rod passes. At the opposite end in the recess in boss 29 is a coiled spring 29^a, bearing against the rod 28, so as to keep the flanges 31 close against its seat, making a tight joint. The operation of this part of the invention is as follows: When it is desired to open the valves when the engine is at rest, the hand 30 is actuated by turning rod 28, which by reason of its eccentricity or oblong shape presses the diaphragm outward and opens the valves. The valve will then be kept open until the handle is reversed, when the diaphragm will be allowed to collapse and the valves to be seated.

For allowing any drip to escape from the valve caused by condensation when steam is employed to operate the same I provide a

drip-valve 32, consisting of a short coupling 55 screwed into the rim 1 and communicating with the interior of the valve. This coupling is provided with a central bore, within which works a headed valve 33. This valve is held normally open by means of a coiled spring 60 34; but when air or steam is admitted to open the cylinder-valve this valve 32 is closed by the pressure thereof upon its head 35.

Having thus described my invention, what I claim is—

1. In a duplex drip-valve for steam-engine cylinders, the combination, with the heads or ends and the rim forming a space connected with a steam or compressed-air supply, of diaphragms located in said space, pipes connecting the heads or ends with the steam-cylinder, and spring-actuated valves in said heads or ends operated by said diaphragms, substantially as described.

2. In a drip-valve, the combination, with a rim having an opening communicating with a supply-pipe provided with a three-way cock, of the heads or ends communicating with a steam-cylinder and provided with spring-actuated valves, and diaphragms for opening said valves, substantially as described.

3. In a drip-valve, the combination, with a rim, heads or ends carrying spring-actuated valves, and the diaphragms, of an eccentric-bar having one end extending outside the rim and provided with a handle, substantially as described.

4. In a drip-valve, the combination, with a rim, heads or ends having spring-actuated valves, and the diaphragms, of an eccentric-bar having one end stepped in a recess in a boss on the rim, a spring located in said recess and bearing against the bar, a beveled flange on said bar, and a coupling having a seat for the flange, substantially as described.

5. In a drip-valve, the combination, with a rim, heads or ends having spring-actuated valves, and diaphragms for operating said valves, of a drainage-valve in said rim, substantially as described.

In testimony that I claim the foregoing as my own I have hereunto affixed my signature in presence of two witnesses.

HARRY HOWELL.
